TOTE RACK FOR NAILS OR THE LIKE

Joseph J. Langworthy, 1818 Bissell Ave.,
Richmond, Calif. 94801

Filed Feb. 1, 1971, Ser. No. 111,784

Term of patent 14 years

Int. Cl. D3—99

U.S. Cl. D87—1

FIG. 1 is a top plan view of a tote rack for nails or the like showing my new design.

FIG. 2 is a side elevational view thereof; and
FIG. 3 is a bottom plan view thereof.

I claim:

The ornamental design for a tote rack for nails or the like, substantially as shown.
